UNITED STATES PATENT OFFICE.

JOHN T. OBENCHAIN, OF LOGANSPORT, INDIANA.

GRINDING-MILL.

SPECIFICATION forming part of Letters Patent No. 253,415, dated February 7, 1882.

Application filed August 19, 1880. (No model.)

To all whom it may concern:

Be it known that I, JOHN T. OBENCHAIN, a citizen of the United States, residing at Logansport, in the county of Cass and State of Indiana, have invented certain new and useful Improvements in Grinding-Mills, of which the following is a specification.

My invention relates to an improvement in grinding-mills.

10 The invention consists in the combination of a millstone and an annular ring in which it is arranged with an outer concentric ring arranged to create an annular space between the two rings for receiving weights, and partitions arranged in said annular ring to prevent the weights from shifting during the rotation of the stone.

15 The invention consists, also, in a novel combination, with the millstone-spindle, of a tram-pot, a ring, pivots supporting the tram-pot, pivots on which the ring is suspended, and a bridge-tree supporting the pivots of the ring, all as more fully hereinafter described in detail.

20 The invention also consists in a novel combination of a journal-bearing, a ring, adjustable pivots supported by the ring, and on which the journal-bearing is suspended, lugs secured to the main frame, and pivots passing through 30 the lugs and sustaining the said ring.

25 The invention also consists in the combination, with the lower spindle of a two-part mill-spindle, of a feed-saucer detachably connected with the upper end of the lower spindle at a 35 point below the face and within the body of the lower running-stone.

30 The invention also consists in a balanced pivoted pressure-plate and lever arranged upon the hopper, with a floator plate portion adapted to be held down or kept from rising by the weight of the material or charge in the hopper, in combination with a swinging bridge-tree and devices adapted, by connection with the pressure-plate lever, to raise the bridge, and 40 to admit, after their disconnection from said lever, of the shifting of the bridge so as to remove the grinding-pressure from the millstones.

35 The invention also consists in a pressure-plate and lever, in combination with tripping devices arranged to automatically remove the

grinding-pressure from the millstone, as the charge of grist leaves the hopper, by shifting the bridge and the running-stone.

Other features of the invention will be hereinafter described, and specifically set forth in the claims.

Figure 1 is a vertical elevation, partly broken and in section, showing my improved mill with its parts in position for grinding. Fig. 2 is a vertical elevation, showing the mill with its parts in position when the stones are at rest. Fig. 3 is a vertical cross-section on line *xx*; Fig. 2, but showing a different preferred form of feed or drop tube adjustment, and omitting the gravitating-lever and its accessories. Fig. 4 is a plan or top view of the lower millstone and the bands or rings encompassing it, but having sufficient space between them for the introduction and adjustment of balancing-weights. Fig. 5 is a plan or top view of the upper stone and its immediate connecting and supporting parts and the preferred form of feed-tube adjustments. Fig. 6 is a vertical sectional elevation of a portion of an upper-running mill, showing the manner of applying my improved automatic devices for raising the upper stone to throw it out of grinding-connection with the lower stone.

A' represent the frame of the mill; A'', the curb for the lower or running stone.

B represents a swinging bridge-tree; B', an adjustable rod by which the bridge-tree is suspended and adjusted.

C represents the spindle on which the stone runs.

C' represents a disk attached to the shaft C by means of a hub, P. On the periphery of this disk is a flange or ring, C'''.

C'' represents a secondary ring concentric with the inner ring, C', and attached to it in any suitable manner, but leaving between these two rings an annular space, *a*, into which weights are placed at suitable points to balance the running of the stone.

c' represents divisions of the annular space *a*, so as to hold the weights in proper position to balance the stone.

D represents the under or running stone, securely attached to the inside of the ring C'.

d represents the eye of the stone D, which is much larger than the spindle C, and it is

filled with plaster-of-paris or other suitable cement, attaching the stone firmly to the spindle. The spindle C passes only part-way through the eye of the stone. In the top end 5 a female screw-thread is cut.

c represents the supplemental end of the spindle C, which is attached to spindle C by a screw-bolt, as shown in Fig. 3. The removable portion c is used as a feed-saucer. It is 10 made removable so that it can be taken off out of the way to allow the use of a diamond dresser.

d' represents a metallic plate or lining, covering the plastic-filled eye of the stone and extending from the spindle to a point near the inner end of the furrows. The inner periphery of the stone is beveled off to allow disk d' to be seated in a plane slightly below the bottom of the furrows. This disk furnishes a 20 smooth continuous surface for the grain to fall upon from the feed-saucer or spindle end, and secures an even distribution of the material to the several encircling furrows. It is readily removable, so that it will not be injured in 25 dressing the stone, and to allow the eye of the stone to be dressed down, so that disk d' can be kept in the same relative plane.

G represents the upper stone, securely set within a ring, g.

30 g' represents an outer concentric ring; F, an upper hinged curb; f, pivots which pass through lugs on the top of curb F. The points press against the outer ring, g', and suspend the same.

35 F' represents bolts passing through ring g and gimbaling the upper stone, G, on their points, these two sets of gimbaling-pivots, f and F', being placed in axial planes at right angles to each other, form a universal joint, 40 which secures the automatic trammimg of the upper stone to the lower stone.

I represents a ring, in which tram-pot I' is suspended by means of the pivots i i. Ring I is in turn suspended on pivots i' i', set at right 45 angles with the plane of pivots i i, and these two sets of pivots, in conneection with the ring I, tram-pot I', and bridge-tree B, form a universal self-adjusting tram-pot, allowing the spindle C to run on its step free from binding

50 and with but a small amount of friction. The upper journal-bearing is formed in like manner of two concentric rings, K L, secured and gimbaled on the frame by means of lugs l and pivots K' and l', which form a universal self-adjusting upper bearing for the mill-spindle.

H represents spider-arms. Three or more should be employed having at their common centers a circular aperture through which passes the feed-spout.

60 H' H' represent posts projecting from the top of curb F, for supporting spider-arms H.

h represents one of the posts having screw-threads engaging in a female screw in one end of arm H, acting as a post and adapted to 65 raise and lower hopper M, suspended thereby.

U u' represent another set of spider-arms, with feet w, and v a set-screw, for raising and

lowering the tube m, suspended in the hub of spider U, through the center of which the feed-tube m' passes. By adjusting the screw v the 70 feed-spout m can be adjusted to or from the feed spindle or saucer e, and the feed or supply of grain from the hopper M regulated with great nicety.

O represents a scale-beam, suspended on 75 post N by knife-edged pins.

o represents a forked end, grasping or engaging with screw-washer o' on the rod B', which suspends bridge-tree B.

O' represents a weight, which can be set to 80 counterbalance the weight of the stone suspended on the bridge-tree to obtain the grinding-pressure on the stones.

P' represents a tripping-rod, which is suspended on trunnions n, turning in journals on 85 post N.

n' represents a cam on the short shaft between trunnions n.

r represents a cam-lever projecting up from scale-beam O. The turning of the tripping-rod P' over to a horizontal position, as shown in Fig. 2, carries cam n' against cam-lever r, and elevates the weight O', lowering bridge-tree B, and separating the stones by removing the grinding-pressure from the bridge-tree. 95

P'' is a weight on tripping-rod P', and is adjusted so as to overbalance weight O' and elevate the scale-beam O.

R represents a balance-lever, pivoted to hopper M by pivot r'.

100 S represents a plate on the end of lever R, which is made of such shape as to lie against the side of the hopper M when the rod R is in a horizontal position. (Shown in Fig. 1.)

T represents a hook on the end of rod P', 105 bent to engage over the lever R and act as a catch. Float or plate S is held down by the material in hopper M, resting upon the same. When the material in the hopper has been ground float S rises, the outer end of lever R 110 falls, releasing the weighted tripping-rod P', which turns over horizontally, overbalancing weight O', and automatically removing the grinding-pressure from the running-stone the instant the grist or charge in the hopper is 115 ground.

Instead of arranging the float S on the inside of the hopper, a hole may be cut in the hopper and covered by a flexible diaphragm of leather or similar material, and the pressure-plate be made to press up against the diaphragm on the outside, the lever being pivoted under the hopper, so as to allow the weighted end to drop and to throw the tripping device as the grain leaves the hopper. 120 125

Fig. 6 represents the tripping devices applied to an upper-run mill.

R' represents the weighted lever, and S the pressure-plate in the hopper; R'', the tripping-rod; Q, a cam on the end of rod R''; R''', a lifting-lever, hinged at p' to the frame of the mill; o', a set-screw suspending rod B'. When tripping-rod R'' turns over to a horizontal position (shown by dotted lines) cam Q raises le-

ver R'', rod B', bridge-tree B, and stone S'', causing it to run clear of the face of the lower stone.

The concentric rings C' C'' and the disk and hub may be cast in one piece with the circular pockets cored or cast in the periphery, and still embody the features shown in the drawings. So, also, instead of suspending the rings on the points of pivots the several pivots may 10 be used as trunnions to journal the rings upon the points, instead of gimbaling the parts on, and still accomplish the objects stated above as features of my invention.

What I claim is—

- 15 1. The combination of the millstone and the annular ring in which it is arranged with an outer concentric ring arranged to create an annular space between the two rings for receiving weights, and partitions c', arranged in 20 said annular space to prevent the weights from shifting during the rotation of the stone, substantially as and for the purposes described.
- 25 2. In a grinding-mill, the combination, with the spindle, of the tram-pot I', the ring I, the pivots i i, supporting the tram-pot, the pivots i' i', on which the ring is suspended, and the bridge-tree having bearings supporting the pivots of the said ring, substantially as and for the purpose described.
- 30 3. In a millstone-bush, the combination of the journal-bearing L, the ring K, the adjustable pivots K' K', supported by the ring, and on which the journal-bearing is suspended, the lugs l, and the pivots l', passing through the lugs and sustaining the said ring, substantially as and for the purpose described.
- 35 4. In a two-part millstone-spindle, the combination, with the lower spindle, of the part e, constituting a feed-saucer, and detachably connected with the upper end of the lower spindle at a point below the face and within the body of the lower running-stone, substantially as and for the purpose described.
- 40 5. A balanced pivoted pressure-plate and lever arranged upon the hopper, with the float or plate portion adapted to be held down or kept from rising by the weight of the material or charge in the hopper, in combination with the swinging bridge-tree and devices adapted by

connection with the pressure-plate lever to 50 raise the bridge, and to admit, after their disconnection from said lever, of the shifting of the bridge, so as to remove the grinding-pressure from the millstone, substantially as herein set forth.

6. In combination with the pivoted lever R and float S, the tripping-rod P', scale-beam O, swinging bridge-tree B, and rod B', substantially as herein set forth.

7. The pressure-plate S and lever R, in combination with tripping devices arranged to automatically remove the grinding-pressure from the millstone, as the charge or grist leaves the hopper, by shifting the bridge and the running-stone, substantially as herein set forth.

8. The combination, with the lower running-stone, D, the upper stationary stone, G, the outer surrounding curb, F, the hopper and the double feed-tube composed of the outer tube, m, and the inner tube, m', of the vertically-adjustable spider U, connected with the outer tube and supported directly on the upper surface of the stationary stone, and the vertically-adjustable spider H, connected with the inner tube and supported by the curb, said members being arranged, substantially as described, for adjusting both parts of the double feed-tube, for the purposes set forth.

9. The combination, with the lower running and upper stationary stones, the surrounding 80 curb, the hopper, and the double feed-tube, composed of the outer and inner movable tubes, of the spider U, connected with the outer tube, and having the arms u u' and adjusting-screw v, supported by the upper surface of the stationary stone, for adjusting the outer tube, and the spider H, supported by standards rising from the curb and connected with the inner tube, and provided with the set-screw h, for adjusting the inner tube, all substantially in the 85 manner and for the purpose set forth.

In testimony whereof I have hereunto set my hand in the presence of two subscribing witnesses.

JOHN T. OBENCHAIN.
